DESIGN FOR A CAP FOR MILK BOTTLES

Raymond Mudge, Detroit, Mich.

Application July 17, 1944, Serial No. 114,431

Term of patent 7 years

(Cl. D58—26)

To all whom it may concern:

Be it known that I, Raymond Mudge, a citizen of the United States, residing in the city of Detroit, county of Wayne, and State of Michigan, have invented a new, original, and ornamental Design for Caps for Milk Bottles, of which the following is a specification, reference being had to the accompanying drawing, forming part thereof.

Fig. 1 is a perspective view of my cap for milk bottles showing my new design.

Fig. 2 is a side elevation thereof.

Fig. 3 is a top view thereof.

I claim:

The ornamental design for a cap for milk bottles, as shown.

RAYMOND MUDGE.
